SWITCH ASSEMBLY

Edgar L. Lees, Youngstown, Ohio

Application June 19, 1946, Serial No. 677,657

4 Claims. (Cl. 200—35)

1

This invention relates to the general art of electric circuit makers and breakers and more particularly to a simplified unitary assembly which may readily be associated in an operative manner with an alarm clock or other actuated means whereby an electric circuit may be opened, or closed, in an automatic manner as desired.

Circuit makers and breakers of the above general character have found wide application for use in turning on or off various appliances such as radios, lighting fixtures etc., at a predetermined time or in response to operation of an actuator as will be understood. It is the primary object of the present invention to provide a switching device which is exceedingly simple in design and economical to construct but which is nevertheless rugged and durable and entirely safe in operation.

Another object of the invention is the provision of a simply constructed portable electrical connector embodying a simplified switch structure which is operative, upon actuation, to open or to control an electric supply circuit passing through the connector.

A still further object of the invention is the provision of an improved electric terminal connector having current input conductors and a plurality of outlets of the quick detachable type for cooperation with conventional line cord plugs, together with a simplified switching arrangement whereby certain of the output circuits are opened while at least another output circuit is simultaneously closed upon actuation of the switch operator.

The above and other specific objects and advantages of the invention will become apparent upon consideration of the following detailed specification and the accompanying drawing wherein there is disclosed certain preferred embodiments of the invention.

In the drawing:

Figures 1 and 2 are rear and side elevations, respectively, of a switching and connecting device constructed according to the principles of the invention, the view showing a possible operative association of the device with a conventional alarm clock;

Figures 3 and 4 are end and front elevations, respectively, of the insulating housing of the device of the invention;

2

Figures 5 and 6 are sectional views taken along the lines V—V and VI—VI of Figures 4 and 3, respectively;

Figures 7 and 8 are plan and side views, respectively, of a modified form of switching and connecting device; and

Figures 9 and 10 are front and sectional views respectively, of the device of Figures 7 and 8.

Referring to the drawing in detail, the device 10 of the invention when associated with the conventional alarm clock (shown in dotted outline at 10) may be mounted on a suitable base 11 which may, in turn, have suitable means for also supporting and retaining the body or housing 15 of the clock. In the embodiment of the device of Figures 1 thru 6 there is provided a housing which is preferably molded of suitable electrical insulating material having adequate mechanical strength as rubber or a resinous plastic for example and, as shown, this housing may consist of a plate-like bottom piece 12 and a multiple recessed upper member 13.

Rigidly secured in recesses formed in member 13 is a pair of electrically conductive spring contacts 14 and 15 suitably spaced and oriented to cooperate with the pair of prongs of a conventional line cord plug 16. It should be observed that the housing member 13 is provided with suitable slots to enable the prongs of plug 16 to enter the body of member 13 to frictionally engage the spring contacts 14 and 15. In the illustrated embodiment a second pair of spring contacts 17 and 18 is rigidly secured in recesses in the body member 13 for cooperation with the prongs of a second cord connecting plug, not shown. Positioned between the two pairs of spring contacts mentioned above is a switch arm 19 rotatably mounted on a screw 20, the head of which retains the arm in assembled relation. By referring to Figure 6 it will be noted that spring contact 15 is formed with an integral lug 21 adapted to be engaged by a lug 22 formed integrally with the arm 19. Another pair of lug contacts 23 and 24 are formed integrally on the contact 17 and arm 19, respectively, and these last named lugs are arranged to have normal pressure contact with each other by means of a spring 25 which normally biases the arm 19 in a counterclockwise direction as viewed in Figure 5. Lugs 23 and 24 may, however, be separated by insertion of an

insulating bar 26 through an aperture formed in the top wall of the housing member 13. To facilitate entry of the separating bar 26 into the body of the switch and between the lugs 23 and 24 the entering end of the bar is eased or tapered as is also the top edge of the aperture formed in member 13. Similarly the upper edges of the lugs 23 and 24 are bent or curved outwardly as shown in Figure 6. Upon insertion of bar 26 and bottoming of the same on member 12 the switch arm 19 will be moved in clockwise direction as viewed in Figure 5 to bring the lug 22 into pressure engagement with the lug 21 of the contact 15.

An end wall of member 13 is provided with an aperture 27 to receive a cord enclosing line conductors 28 and 29. Shown in Figure 1 these conductors may be connected in any suitable manner with a current source and by referring to Figure 5 it will be noted that the conductor 28 is electrically connected to the switch arm 19 while the conductor 29 is electrically connected to both the spring contacts 14 and 18. Now it should be apparent that upon insertion of the bar 26 in the manner described above the contacts 14 and 15 will be electrically connected with the current source while the contacts 17 and 18 will be open-circuited with respect to the source. Thus, an appliance connected to contacts 14, 15 will be operative while an appliance connected to contacts 17, 18 will be held inoperative. If the bar 26 is now retracted the circuit fed from contacts 14, 15 will be opened while the circuit fed from contacts 17, 18 will be closed.

In accordance with usual practice the various contacts and conductors may be assembled in the housing member 13 after which the bottom member 12 is applied and secured to member 13 to close the body of the assembly as will be understood. Bar 26 is preferably apertured at its outer end to receive an operating cord 30 which may be connected to the alarm wind key 31 as shown in Figures 1 and 2 whereby the bar 26 may be withdrawn or retracted at a predetermined time upon actuation of the alarm in the clock, it being understood that the wind key 31 will commence to rotate in a direction opposite to its winding direction upon release of the alarm train in the clock.

The embodiment of Figures 7 thru 10 is generally similar to the form first described but differs therefrom in general arrangement and in the use of a switch contact having an inherently flexible arm operative upon retraction of the insulating separator bar to move into pressure engagement with a spring contact positioned in a circuit which is to be turned on upon removal of the bar. In this modification there is again provided a housing having a plate-like bottom member 31 and a recessed upper housing member 32 arranged to be rigidly connected together upon final assembly of the apparatus. Mounted in recesses in the member 32 is a pair of spring contacts 33 and 34 forming one circuit outlet and a second pair of spring contacts 35 and 36 forming the second circuit outlet. As in the embodiment first described each of these circuit outlets may be engaged by conventional cord connecting plug. Contact 33 has an integral switch contact lug 37 and contact 35 has a similar integral switch contact lug 38. Arranged to contact lugs 37 and 38 alternately is a contact 39 carried by the outer end of a flexible spring arm 40. Arm 40 normally biases contact 39 into pressure engagement with lug 37 while upon insertion of the

insulating separator bar 26 through the aperture formed in the top wall of member 32 and between the contacts 37 and 39 the contact 39 will be moved into pressure engagement with the contact lug 38. One of the current supply conductors, as 41 is electrically connected to spring contacts 34 and 36 while the other of the supply conductors 42 is electrically connected to the arm 40. By reason of this arrangement one of the outlet circuits is opened while the other is closed upon retraction of operator 26 and the converse occurs upon insertion of the operator as will be understood.

It should now be apparent that I have provided an improved and simplified electric circuit making and breaking apparatus which accomplishes the objects initially set out. The apparatus is exceedingly simple in design and most economical to construct and is readily adaptable for a wide variety of uses in association with time controlled or other operating means, including manual means. Further, the incorporation in the switching assembly of conventional outlet receptacles further enhances the usefulness of the complete structure. The above specifically described embodiments of the invention, however, should be considered as illustrative only as obviously many changes may be made therein without departing from the spirit or scope of the invention. Reference should therefore be had to the appended claims in determining the scope of the invention.

What I claim is:

1. A switch mechanism comprising in combination an insulating housing, a pair of electrically conductive spring contacts secured in said housing and adapted to be engaged by the prongs of a conventional line cord plug, a movable switch arm in said housing and normally biased to predetermined position with respect to one of said spring contacts, a switch contact on said arm adapted to move into and out of engagement with said one of said spring contacts upon movement of said arm, an aperture in one wall of said housing, and a retractile insulating bar slideably received in said aperture and operative when fully inserted in said aperture to retain said arm away from its normally biased position.

2. A switch mechanism comprising in combination an insulating housing, two pairs of electrically conductive spring contacts secured in said housing and adapted to be engaged by the prongs of a pair of conventional line cord plugs, a movable switch arm in said housing and normally biased to predetermined position with respect to one of each of said pairs of spring contacts, a switch contact on said arm adapted to have alternate engagement with said one of each of said pairs of spring contacts, and retractile means engaging said arm to retain said arm away from its normally biased position whereby upon retraction of said means a circuit including one of said pairs of spring contacts is opened while a second circuit including the other of said pairs of spring contacts is closed.

3. A switch mechanism comprising in combination an insulating housing member having a top wall and side and end walls, a pair of spring contacts secured in depending relation to said top wall and adapted to be engaged by the prongs of a conventional line cord plug, a movable switch arm also suspended from said top wall and normally biased to predetermined position with respect to one of said spring con-

tacts, a switch contact on said arm adapted to move into and out of engagement with said one of said spring contacts upon movement of said arm, retractile means to retain said arm away from its normally biased position, and a separable plate-like housing member for closing off the bottom of the first mentioned housing member.

4. An assembly according to claim 3 further characterized in that said retractile means consists of an insulating bar slideably received in an aperture in said top wall and operative

when fully inserted in said aperture to retain said arm away from its normally biased position.

EDGAR L. LEES.
